PIPE HANDLING APPARATUS

Bowman W. Gray, Odessa, Tex.

Application July 20, 1951, Serial No. 237,777

2 Claims. (Cl. 214—2.5)

1

This invention relates to apparatus for conveying pipe from a well to a rack or storage location.

When removing pipe from a well, the pipe sections, which are approximately thirty feet in length, are pulled vertically upwardly by a derrick or the like, and when the lower end is clear of the ground and is disconnected from the succeeding section, the present practice is to hook the lower end of the pipe section to a sheave mounted for movement along a taut cable extending from the derrick. One of the difficulties encountered in the present practice is the dropping of the pipe onto a rack or pile in an even manner.

Another difficulty in the present practice is the lack of automatic equipment for releasing the outer end of the pipe at a predetermined lateral location.

It is, therefore, an object of this invention to provide means for automatically releasing the pipe at a predetermined point in the lateral movement thereof so that the pipe may be stacked in an even pile.

A further object of this invention is to provide a conveying device which can readily be adapted for conveying elongated heavy rods, boxes or bundles of material.

With the above and other objects in view, my invention consists in the arrangement, combination and details of construction disclosed in the drawings and specification, and then more particularly pointed out in the appended claims.

In the drawings:

Figure 1 is a longitudinal section of a carrier for conveying a pipe which is constructed according to an embodiment of this invention.

Figure 2 is a sectional view taken on the line 2—2 of Figure 1.

Figure 3 is a sectional view taken on the line 3—3 of Figure 1.

Figure 4 is a fragmentary side elevation showing an attachment adapted to be used with the carrier.

Figure 5 is a fragmentary bottom plan of the attachment shown in Figure 4.

Figure 6 is a fragmentary side elevation partly in section showing another attachment or accessory for use with this invention.

Figure 7 is a fragmentary sectional view taken on the line 7—7 of Figure 6.

Figure 8 is a rear elevation of the accessory shown in Figures 6 and 7.

Referring to the drawings, and, first, to Figures 1, 2, and 3 the numeral 10 designates gen-

2

erally a carrier frame structure which is formed of side frame members 11 and 12 and a top wall 13. A pair of grooved wheels 15 and 16 are rotatably mounted on transversely disposed shafts 17 and 18, respectively. The grooved wheels 15 and 16 ride over a relatively taut cable 19 which is preferably inclined to the horizontal and is normally extended from a well derrick to a remote point where it is intended to store pipe which has been withdrawn from the well.

The frame structure 10 also includes a transversely disposed bar 20 at the forward end of the frame which is secured between the side members 11 and 12, and the bar 20 has secured therein a rubber bumper or guide 21. A pipe carrying hook 22 is rockably mounted on a shaft 23 disposed between the side members 11 and 12, and the hook 22 is formed with a bill 24 adapted to engage within one end of a pipe section P.

In order to provide a means whereby the hook 22 will be locked in a pipe carrying position until the carrier 10 has reached a predetermined point along the length of the cable 19, I have provided a latch member 25 which is rockably mounted on a shaft 26 extending between the side members 11 and 12. The latch member 25 includes a latching bill 27 which is adapted to engage a complementary latching bill or keeper 28 which is formed on or carried by the hook 22.

A spring 29 bears at one end against the forward side of the latch member 25 engaging about a lug 30 which is carried by the latch member 25, and the opposite or forward end of spring 29 is seated in a socket 31 which is secured to and supported from one of the side members of the frame, and in the present instance is secured to the side member 12.

The upper end of the latch member 25 has pivotally secured thereto an elongated plunger 32 which is loosely mounted in a cylindrical housing 33. The forward end of the plunger 32 is pivotally connected with the latch member 25 by means of the pivot pin 34. A spring 35 is disposed about the plunger 32 within the housing 33 and bears at its forward end against the forward end wall 36 of housing 33 and bears at its rear end against a collar 37 which is secured on the plunger 32.

The housing 33 is threaded at its rear end into a bushing 38 which is carried by a bracket arm 39, and the arm 39 is provided as at 40 on the inner side of wall 12. The rear end of plunger 32 is formed with a rounded head 41 confronting a plunger operator or lever 42 which is pivotally

mounted on a transversely disposed pin or shaft 43 extending between the side members 11 and 12. The lever or operator 42 is formed with a relatively long slot 44 through which the cable 19 is adapted to loosely engage, and the rear side of the lever 42 is formed with a rounded or cam surface 45 which is adapted to be engaged by a stop member or collar 46 which is clamped to the cable 19 at the point or location where it is desired to drop the pipe P.

The frame 10 has an eye 47 at the forward portion of the top wall 13 with which a cable or flexible member 48 is connected so that the carrier 10 may be returned from its remote discharge position to a receiving position adjacent the derrick.

In order to provide a means whereby the carrier 10 may be adapted for carrying articles other than pipes such as boxes, machine tools, drill collars or the like, a pair of clevises 49 are adapted to be mounted on the shaft 26, and the ends of a chain or sling forming member 50 are connected with the two clevises 49.

Where long rods or the like are to be conveyed from the derrick to a remote position, an attachment is mounted on the hook 22 as shown in Figures 6, 7 and 8. This attachment comprises a socket member 51 having a pair of rearwardly projecting ears 52 which are adapted to engage on opposite sides of the bill 24 of the hook 22. Preferably the bill 24 at its forward end is formed with a notch 53 within which a substantially V-shaped lug 54 carried by the rear of the socket 52 is adapted to engage.

A pin 55 is extended through the ears 52 and through the bill 24 as shown in Figures 6 and 7 so that the socket 51 will be firmly locked to the bill 22.

In the use and operation of this apparatus the carrier 10 is mounted for movement on the taut cable 19, and the stop or release member 46 is clamped about the cable 19 at a point closely adjacent the point of discharge or release of the article from the carrier 10. Where a pipe P is to be conveyed one end of the pipe P is telescoped over the bill 24 of the hook 22, the pipe abutting against a lug 53a carried by bill 24, and at this time the hook 22 is locked against rocking by means of the spring-pressed latch member 25. Lug 53a provides a weight to assist in swinging hook 22 to released position. The pipe is then moved downwardly along the cable 19, and when the releasing lever 42 strikes the stop member 46 plunger 32 will be moved forwardly, thereby re-

leasing latch member 25 from keeper 28 so that hook 22 may rock downwardly and forwardly to a release or discharge position.

Where a sling is to be used which is formed by the chain 50 the hook 22 may be raised upwardly to an out of the way position and held in such out of the way position by means of a pin engaging through aligned openings 56 which are formed in the side members 11 and 12. This pipe or rod conveying device will provide a means whereby the article which is to be conveyed will be moved to a selected location and automatically released from the carrier at such predetermined location.

15 What is claimed is:

1. Pipe handling apparatus comprising a movable frame, a pair of grooved wheels rotatably carried by said frame and engageable on a taut cable whereby said frame may be moved along said cable, a pipe engaging hook rockably carried by said frame, a keeper carried by said hook, a spring-pressed latching member carried by said frame for engaging said keeper to lock said hook in operative position, a latch releasing lever carried by said frame, a spring biased operating connection between said latch and said lever, and a lever operator secured to said cable whereby contact of said lever with said operator will rock said lever to latch releasing position.

20 2. In combination, a taut cable disposed on an inclination to the horizontal, a pipe carrier movable along said cable comprising a frame, grooved wheels rotatably carried by said frame engaging said cable, a pipe supporting hook rockably carried by said frame, a spring-pressed latch carried by said frame, a keeper carried by said hook engageable by said latch for normally holding said hook in operative position, a spring-pressed

25 plunger pivotally connected at one end to said latch, means supporting said plunger in said frame, a latch releasing lever rockably carried by said frame and bearing against the opposite end of said plunger, and a lever operator fixed to said cable adapted to rock said lever to latch releasing position.
